Primary Examiner — Eric Goodman*Assistant Examiner* — Alyse Joseph(74) *Attorney, Agent, or Firm* — Jianq Chyun IP Office(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image in the sequence showing my new design; and,

FIG. 2 is a front view of the second image thereof.

The broken lines around the Figures showing a display screen or portion thereof form no part of the claimed design. The broken lines within the Figures show portions of the animated graphical user interface which form no part of the claimed design.

The appearance of the animated images sequentially transitions between the images shown in FIGS. 1-2. The process or period in which one image transitions to another image forms no part of the claimed design.
